UNITED STATES PATENT OFFICE.

WILLIAM NEIDLINGER, OF NEW YORK, N. Y.

DESIGN FOR LEECH-JAR.

Specification forming part of Design No. 5,508, dated February 6, 1872.

Specification describing a new and original Design for a Leech-Jar, invented by WILLIAM NEIDLINGER, of the city, county, and State of New York.

Figure 1 represents a side view of my new leech-jar. Fig. 2 is a vertical central section of the same.

Similar letters of reference indicate corresponding parts.

This invention relates to a new form of leech-jar; and consists in making the same in form of a druggist's mortar, with an imitation-pestle projecting from its cover.

A in the drawing represents a jar of cylindrical form, and provided with a cover, B, from which an imitation-pestle, C, projects, all being arranged to resemble a mortar, as shown.

I claim as my invention—

The design for a leech-jar, as shown.

WILLIAM NEIDLINGER.
